LAVATORY FITTING

James E. Niemann, Louisville, Ky., assignor to American Standard Inc., New York, N.Y., a corporation of Delaware

Filed Dec. 10, 1969, Ser. No. 20,446

Term of patent 14 years

Int. Cl. D23—01

U.S. Cl. D23—23

FIG. 1

FIG. 2

FIG. 3

FIG. 4

FIG. 1 is a side view of a lavatory fitting embodying the new design;

FIG. 2 is a front elevational view thereof;

FIG. 3 is a top plan view thereof; and

FIG. 4 is a rear elevational view thereof.

I claim:

The ornamental design for a lavatory fitting, substantially as shown.
